EDGE SETTING MACHINE

William Hamann, Irondequoit, N. Y., assignor to
United Shoe Machinery Corporation, Flemington, N. J., a corporation of New Jersey

Original application May 17, 1940, Serial No.
335,725. Divided and this application June 28,
1941, Serial No. 400,179

9 Claims. (Cl. 12—78)

This invention relates to burnishing machines and is illustrated herein as embodied in improved tool holding mechanism for use in a machine for setting the edges of soles of shoes.

In machines such as disclosed in United States Letters Patent No. 2,283,204 granted May 19, 1942, upon an application, of which the present application is a division, there is provided a tool holder which is oscillated at a high speed about a horizontal axis and has a cylindrical opening inclined at slightly less than 90° to said axis, in which opening fits a cylindrical spindle of a carrier to which is secured an edge setting tool. When no work is being presented to the machine, the carrier is moved in the holder to an outward position away from the horizontal axis by a thrust spring operating against the carrier spindle. During the edge setting operation, the operator forces the edge of the sole of the shoe being operated upon upwardly against the tool as he feeds the shoe past the same, causing the carrier spindle to slide in the cylindrical opening of the holder toward the axis of oscillation against the action of the thrust spring.

Machines such as disclosed in said Letters Patent No. 2,283,204 operate at speeds which are considerably higher than those of edge setting machine now in general use. It has been found that the spring type of snap connections commonly used in the slower machines for fastening tools to the tool carriers permits some play between those parts, with the result that there is a constant wear on the tools in the high speed machines. Moreover, the travel of the tool in high speed machines is small and even slight wear between the tools and the tool carriers reduces the movement of the tools until the point is reached where the tools must be discarded.

It is an object of the present invention to increase the life of finishing tools by preventing play between the tools and their carriers and, to this end, there is provided a tool fastening means which will positively prevent lost motion between the tools and the carriers when these parts are vibrated at high speeds and which can be released or tightened so that the tools may be rapidly changed when desired. As illustrated, the tools and the tool carriers are provided with complementally shaped surfaces which are held in interlocking engagement by clamping members. To make sure that there is no play between the tools and the tool carriers, the clamping members may be wrench-operated so that the interlocking surfaces of the tool and the tool

carriers may be jammed forcibly against one another.

The various features of the invention will be understood and appreciated from the following detailed description read in connection with the accompanying drawing, in which

Fig. 1 is a side elevation, partly in section, of the tool head of an edge setting machine in which the present invention is embodied;

Fig. 2 is a front view of the tool head shown in Fig. 1, portions of the head having been removed;

Fig. 3 is a side view of the tool clamping means shown in Fig. 1;

Fig. 4 is a front view of the construction shown in Fig. 3;

Fig. 5 is an angular view of the tool of Fig. 3; and

Fig. 6 is a side view of a wrench for operating the clamping means shown in Fig. 3.

The illustrative tool holding mechanism is described as incorporated in the above-mentioned machine which is disclosed in said Letters Patent No. 2,283,204 and comprises a shaft 20 (Fig. 1) mounted for high speed oscillation in a bearing 22 about an axis 24. Slidably and rotatably mounted in the shaft is a spindle 26 which is connected to a tool holder 28 and is constantly urged in a direction 30 lengthwise of the axis 24 by a spring 32. The shaft is provided with an enlarged head 34, which has a pair of spaced alined notches 36 (Fig. 2) for receiving rearwardly projecting lugs 38 on the tool holder 28 and which, together with the lugs, forms a driving connection for causing the tool holder to move with the shaft.

The tool holder 28 has a pair of bosses 40 each having a cylindrical hole or opening 42 in which fits a spindle 44 of a tool carrier 46. The tool carriers 46 are constantly urged outwardly away from the axis of oscillation 24 by springs 48 which are mounted on posts 50 of the holder 28 and have secured to their inner ends balls 52 adapted to fit in recesses formed at the inner ends of the spindles 44. Outward movement of each of the carriers 46 away from the axis 24 is limited by a leaf spring 54 which is fastened by a screw 56 to an associated boss 40 and has an inner end which, when the machine is idle, is in engagement with a flat bottom face 58 of a recess formed in the spindle 44 of the tool carrier 46. During the edge setting operation, the operator forces the edge of the sole of the shoe upwardly against a tool 60, which is secured, through mechanism which will be described

later, to the carrier 46, as he feeds the shoe past the tool, causing the carrier 46 to slide in the cylindrical opening or hole 42 toward the axis 24 against the action of an associated thrust spring 48.

In order that the shoe may be quickly and effectively moved past the tool 60, it is desirable for the tool to turn slightly about the axis 62 of the carrier spindle 44. When the machine is idle, the carrier 46 is held in a neutral position, in which lengthwise elements 64 (Fig. 4) of the work-engaging face 66 of the tool are parallel to the plane of oscillation of the tool, by the engagement of the flat inner end of the spring 54 with the flat bottom 58 of the recess. It will be appreciated, however, that, during the operation of the machine, there is usually a constant turning of the carrier 46 in the holder 28 about the axis 62 due partly to the pressure of the work against the tool 60 and partly to the fact that the tool carrier and the tool are not statically balanced about the axis 62.

In operating upon shoes, it is common practice to use a forepart tool for setting the edge of the forepart of the shoe and a shank iron for setting the edge of the shank of the shoe. Accordingly, it is desirable for the operator, when operating upon many types of shoes, to rotate the holder 28 180° about the axis 24 in order to interchange the operative positions of the carriers 46 and the tools 60, such movement being effected by the provision of mechanism which is operated by a hand crank 67 and which is described in detail in said Letters Patent No. 2,283,204.

It is desirable frequently to replace the tool 60 by tools having work-engaging faces 66 of different sizes and shapes in accordance with the type of shoe being operated upon and the thickness of the soles of the shoes. Accordingly, in order quickly to replace the tools 60 by tools having work-engaging faces of different sizes and shapes, it has been common practice for years to use spring-type snap connections (not shown) for securing the tools in place on the carriers. It has been found, however, that when such snap connections are used, a slight play soon develops between the carriers and their associated tools, with the result that there is considerable wear between these parts and, in the case of high speed, short stroke tools, the play between the tool and the carrier becomes so great that the tool or the carrier or both must be discarded and replaced by new members.

In the illustrated machine this difficulty is overcome by using clamping means which eliminates lost motion between the tool carriers 46 and the tools 60. The tool carrier 46 and the tool 60 are provided with complementally shaped interlocking surfaces which are held clamped against each other by a transversely extending bolt 68. The tool carrier 46 is relieved to form a wedge-shaped flange having a flat inclined surface or abutment 70 and a horizontal end portion 72 from which extends a finger or tongue 74. It will be noted that the large flat abutment 70 is rigid with relation to the spindle 44. As is best illustrated in Fig. 5, the tool 60 is provided with a wedge-shaped extension having an inclined surface 76, which is sloped complementally to the surface 70 on the tool carrier, and a horizontal shelf 78 in which there is a groove 80 for the reception of the tongue 74 on the tool carrier 46. The bolt 68 extends through a slot 82 (Fig. 5)

in the tool extension, thence through an opening in the tool carrier, and projects a short distance beyond a face 83 (Fig. 3) of the carrier. The projection portion of the bolt 68 is surrounded by a displaceable abutment consisting of a slotted plate 84 pivoted at 85 to the tool carrier 46, a washer 86, and a nut 90. The tool is quickly released from the carrier by a socket wrench 92 (Fig. 6) having a laterally extending finger 94. The finger 94 is arranged so that it will strike the plate 84 after the nut 90 has been backed off slightly, for example, approximately one-eighth of a turn, and will knock the plate from beneath the washer 86, allowing the plate to move bodily to the left, as viewed in Fig. 4, and the tool to be withdrawn along the inclined abutment 70.

It will be appreciated that, when the screw 90 is tightened, a clamping thrust is exerted in directions inclined to the flat faces 70 and 76 of the carrier and the tool, thereby clamping said faces together by a wedging action.

Having described my invention, what I claim as new and desire to secure by Letters Patent of the United States is:

1. In a burnishing machine, a holder mounted for oscillation about an axis and having a cylindrical opening, a burnishing tool, a tool carrier comprising a spindle mounted for rotary and longitudinal movement in said opening, means for urging the spindle longitudinally in the opening to maintain the carrier at a predetermined distance from said axis, said urging means being yieldable to permit said carrier to move under pressure of the work toward said axis, resilient means for yieldably holding the carrier spindle in a neutral position of rotation in said opening, the spindle being rotatable in opposition to said resilient means in either direction from said neutral position under pressure of the work and the resilient means being operable to return the spindle to said neutral position upon release of said pressure, and means for positively clamping the tool to the carrier.

2. In a burnishing machine, a holder mounted for oscillation at a high rate of speed, a burnishing tool, a tool carrier mounted on said holder, said carrier having a flat abutment portion adapted to be engaged by a flat side of the burnishing tool and having a face which is angularly disposed to said abutment portion and is adapted to be engaged by another face of the burnishing tool, means constructed and arranged to engage the opposite side of the burnishing tool and also the tool carrier, and means for forcing the first-named means against the burnishing tool and against the carrier in order to clamp the tool between the flat abutment portion of the carrier and said first-named means.

3. In a burnishing machine, a holder mounted for oscillation at a high rate of speed, a pair of members, one of which is a burnishing tool and the other of which is a carrier for said tool, said carrier having a portion which registers with and through which the carrier is supported in the holder, each of said members having a flat abutment in contact with a flat abutment of the other member, the flat abutment of the carrier being rigid with relation to said registering portion of the carrier, and means for exerting a clamping thrust in directions inclined to said abutments in order rigidly to force said abutments together.

4. In a burnishing machine, a holder mounted

for oscillation about an axis and having a cylindrical hole, a burnishing tool, a carrier for the tool, said carrier comprising a spindle and a flat abutment which is rigid with relation to the spindle, said spindle being shaped and arranged to fit in said hole, a spring constructed and arranged constantly to urge the carrier to a predetermined position away from said axis but to permit the carrier to be moved under pressure toward said axis, said tool having a flat face, and means for clamping the flat face of the tool securely against the flat abutment of the carrier.

5. In a burnishing machine, a holder mounted for oscillation about an axis and having a cylindrical hole, a burnishing tool, a carrier for the tool, said carrier comprising a spindle and a flat abutment face which is rigid with relation to the spindle, said spindle being shaped and arranged to fit in said hole, a spring constructed and arranged constantly to urge the carrier to a predetermined position away from said axis but to permit the carrier to be moved under pressure toward said axis, yieldable means constructed and arranged to enable the carrier spindle to be turned slightly under pressure in the hole but normally to retain the spindle in a predetermined position in the hole, said tool having a flat abutment face, and means for exerting a clamping thrust in directions inclined to said flat abutment faces of the carrier and the tool in order to clamp said faces together by a wedging action.

6. A tool carrier for use in a finishing machine having a vibrating tool holder, said tool carrier having surfaces arranged for locking engagement with a finishing tool, and means for clamping the tool to the tool carrier, one of said surfaces being inclined to the direction of thrust of said clamping means to provide a wedging effect when the clamping means is tightened, said clamping 40

means including a displaceable spacer arranged quickly to be disassociated from the remainder of the clamping means when the latter is loosened thereby speedily to release the tool from the tool holder by permitting withdrawal of the tool along said inclined wedging surface.

7. A tool assembly for use in a finishing machine having a vibrating tool holder, said assembly comprising a tool carrier including a head having an undercut jaw, a finishing tool having a complementally shaped undercut jaw, and a bolt arranged to clamp the jaws of said tool and said head against each other, said carrier and said tool having a tongue-and-groove connection to supplement said jaws in positioning said tool upon the carrier.

8. A tool assembly for use in a finishing machine having a vibrating tool holder, said tool assembly comprising a tool carrier and a tool having complementally shaped interlocking surfaces, a clamp having a pair of oppositely disposed clamping members for exerting pressure through said tool assembly to hold said surfaces against each other, said clamping members consisting of a bolt head and a nut, and a plate swingably mounted on the carrier and arranged to engage beneath one end of said clamping members.

9. A tool assembly for use in a finishing machine having a vibrating tool holder, said tool assembly comprising a tool carrier and a tool having complementally shaped interlocking surfaces, a clamp having a pair of oppositely disposed clamping members for exerting pressure through said tool assembly to hold said surfaces against each other, and a plate engageable between said tool assembly and one of said clamping members, said plate being mounted for ready removal to facilitate disassembly of said tool assembly.

WILLIAM HAMANN.
